UNITED STATES PATENT OFFICE.

CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

PRIMARY-VOTING MECHANISM.

1,127,149.

Specification of Letters Patent.

Patented Feb. 2, 1915.

Application filed July 14, 1911. Serial No. 638,548.

To all whom it may concern:

Be it known that I, CHARLES C. ABBOTT, a citizen of the United States, residing at Pittsfield, county of Berkshire, State of Massachusetts, have invented an Improvement in Primary-Voting Mechanism, of which the following is a specification.

This invention relates to voting machines used in primary voting and to those features 10 of voting machines of general utility as adapt them for use for this purpose. The laws in some localities require that a primary voter declare his party before entering the machine to vote. That portion of the 15 machine which corresponds to the nominees of the party so declared is thereupon unlocked to permit voting for such nominees, the remainder of the machine being locked against operation. These laws, however, 20 usually permit the primary voter to vote independently, that is to say for nominees of his own choosing rather than for the regular party nominees. In the latter case, however, the vote of the independent voter must be 25 identified as to party.

In another application filed January 2, 1912, Serial No. 669,252, there is shown and described primary voting mechanism arranged to unlock the voting members of a 30 voting machine which correspond to the regular nominees of any desired party, leaving the remainder of the machine locked.

It is the object of the present invention to provide independent voting mechanism by 35 the use of which a primary voter may vote for nominees of his own choice but which will cause the party of the voter so voting to be recorded by the machine.

With the above and other objects in view I 40 have devised the novel mechanism which I will now describe, referring to the accompanying drawings forming a part of this specification and using reference characters to indicate the several parts:

45 Figure 1 is a view, looking toward the back of the machine, of the paper marking mechanism; Fig. 2 is a transverse vertical section of a portion of the machine, the line of section being indicated by the line 2—2 in 50 Fig. 1; Fig. 3 is an elevation partly broken

away of a portion of the front of the machine; Fig. 4 is a section on the line 4—4 in Fig. 3; Fig. 5 is a detail elevation of one end of one of the party lines showing the corresponding party lever in section; Fig. 6 is a 55 plan view, partly in section, of the parts shown in Fig. 5; Fig. 7 is a front elevation of a portion of the paper feed mechanism showing one of the shutters used in independent voting.

The invention is herein shown as applied to a machine of the type shown and described in Letters Patent Number 914,006, granted to me March 2, 1909, and in an application for Letters Patent filed by me July 28, 1909, Serial Number 509,991, said machine being provided with independent voting mechanism of the general character disclosed in Letters Patent Number 914,007, granted to me March 2, 1909. The machine 70 shown in the first patent referred to is a horizontal machine, so called, in which the names of party candidates are placed in horizontal lines, called party lines, and the names of all candidates for the same office 75 are placed in vertical columns, called office columns, although of course the mechanism may be arranged otherwise if preferred.

12 denotes the framework of the machine which is formed of sheet metal forming a 80 casing and providing the necessary supports, guides and bearings for the various parts of the machine except as hereinafter pointed out.

13 (see Figs. 5 and 6) denotes the voting 85 members as a whole, these voting members comprising oscillatory shafts journaled in the framework and having voting levers 14 lying outside the machine at the back. Turning of these voting members from the 90 non-voting to the voting position places them in a position to cause an operation of suitably arranged counters corresponding in number to the voting members. This counting mechanism is not shown herein as it 95 forms no portion of the present invention and is fully disclosed in Letters Patent Number 914,006, above referred to.

15 denotes one of the party bars, which correspond in number with the party lines 100

of the machine, and 16 the resetting bars which correspond in number with the party bars.

17 denotes arms on the voting member shafts, said arms carrying pins 18 which pass through slots 19 in the resetting bars and through slots 20 in the party bars.

21 denotes the party levers pivoted in the framework and extending through slots in the front plate. The inner end of each party lever extends through a slot 22 in the corresponding resetting bar and through a slot in a link 23 connected to the corresponding party bar by means of a stud 24 which passes through a slot 25 in the corresponding resetting bar.

26 denotes studs or lugs riveted to the ends of the resetting bars 16.

The voting mechanism thus far referred to is, in a general way, well known in the art and will, it is thought, be understood without further description. The specific construction and arrangement of the voting members and associated parts form no portion of the present invention.

The normal or non-voting position of the parts is shown in Figs. 5 and 6. With the parts in this position the pins 18 carried by the voting members 13 are in engagement with the left ends of the slots 19 in the resetting bars 16, as shown in Fig. 5. The voting members cannot therefore be turned into voting position, or rotated in a clockwise direction as shown in said figure, without causing a movement of the corresponding resetting bar 16 from right to left.

27 denotes primary locking bolts or members. These bolts are equal in number to the number of lines of voting members, are guided in suitable parts of the framework, and are movable from an inoperative or retracted position into an operative position in which their rear ends are in engagement with the studs 26 riveted to the ends of the resetting bars 16. This operation will best be understood from Fig. 6 in which a bolt 27 is shown in inoperative position. When moved into operative position, or downwardly as shown in said figure, the end of said bolt lies adjacent the corresponding stud 26. As shown in Figs. 5 and 6, the resetting bar is in its extreme position toward the right and the corresponding bolt 27, when in operative position, serves to lock the bar 16 in this extreme position, and, by engagement of the pins 18 with the ends of the slots 19, to lock the voting members in the corresponding line in non-voting position.

28 denotes a key bar or carrier slidably mounted in a guideway formed by the front of the machine casing, through which the forward ends of the bolts 27 project, and a cover plate 29 secured thereto, said cover plate having an index opening 30.

31 denotes party markers arranged according to statutory provision and each designated by an identifying symbol, herein shown as letters "A," "B," "C," etc.

32 denotes keys secured to the key bar 28 and comprising flat strips of metal bent to form angular offsets or cam portions 33.

The locking bolts 27 are provided with notches 34 adapted to receive the edges of the keys 32.

The arrangement is such that when the straight portion of any key is in engagement with the notch 34 of the corresponding bolt, as shown in Fig. 4, said bolt will be retracted or moved toward the right in said figure into locking position with its rear end in engagement with the lug 26 on the resetting bar 16, thereby locking the corresponding party line. When the key bar 28 is moved to bring the cam portion 33 into engagement with the notch 34, as shown in Fig. 3, the bolt is moved forwardly or toward the left in Fig. 4 and the corresponding line unlocked. The keys 32 are equal in number to the lines of voting members, and the cam portions 33 thereof may be so arranged upon the key bar as to provide for the unlocking of one line only at a time or the simultaneous unlocking of several lines in accordance with the requirements, as where the candidates of one party occupy more than one line. For example, as indicated in Fig. 3 the candidates of party "A" will be understood to occupy the first and second lines from the top, those of party "B" the third and fourth, and so on. The key bar 28 is provided with symbols or letters corresponding to the symbols displayed by the party markers 31, these symbols or letters being arranged to be brought successively opposite the opening 30 as the key bar 28 is moved longitudinally in its guide.

The arrangement of the offset portions 33 of the keys is such that when the symbol "A" on the key carrier is opposite the index opening 30, party line or lines "A" will be unlocked and the remaining party lines locked; when the symbol "B" is opposite the index opening, party line or lines "B" will be unlocked and the others locked; and so on.

35 denotes a shaft journaled in the framework and provided outside the casing with an operating knob or handle 36. The shaft 35 carries a pinion 37 (Figs. 2 and 4) cooperating with rack teeth 38 (Fig. 3) formed on the key bar 28. By rotating the shaft 35 the key bar can be moved longitudinally to bring any desired symbol opposite the index opening 30. The keys 32 are preferably detachably connected with the key bar 28 and may be arranged thereon according to requirements, as where the nominees of a party occupy a plurality of lines. The shaft 35 is therefore made longitudi-

nally movable in its bearings to a limited extent sufficient to carry the pinion 37 into and out of engagement with the rack 38 in order to permit the key bar 28 to be removed 5 from the bottom of the cover plate 29 for the purpose of arranging the keys.

The primary locking mechanism thus far described is substantially the same as that disclosed and claimed in my co-pending application Serial Number 669,252, above referred to.

39 (see Fig. 7) denotes voting apertures in the rear of the casing which are covered by shutters 40 sliding in ways 41 on the 15 inner side of the rear plate.

42 (see Fig. 2) denotes the independent voting paper strip which is drawn from a suitable source of supply by means of a feed roll 43 (Figs. 2 and 7) journaled in brackets 20 44 supported from the framework.

45 denotes a backing plate over which the paper strip passes and which is rigidly secured in place contiguous to apertures 39.

46 denotes the feed shaft which is suitably 25 journaled in the framework, passes loosely through the feed roll 43, and is rotated by suitable connections with the entrance and exit mechanism which is operated by the voter when he enters and leaves the machine. These connections and mechanisms are not shown as they form no part of the present invention and are more fully disclosed in my prior patents above referred to.

Feed roll 43 is provided with a clutch 35 member 47 co-operating with a clutch sleeve 48 rotating with the paper feed shaft 46 but longitudinally movable thereon.

49 denotes an actuating slide which reciprocates in suitable ways in the machine 40 frame and is connected with the clutch sleeve 48 by means of a clutch shifter 50.

51 denotes a link connected at its lower end with one of the interlocking members of the machine and having at its upper end 45 an inwardly projecting head 52.

The rear or face plate of the casing is provided with a series of openings 53, the upper portion of the left side of which (as shown in Fig. 7) consists of an incline 54.

50 55 denotes openings in actuating slide 49.

At the upper end of each shutter 40 is a reduced portion 56 terminating in an incline 57.

When a shutter is in the closed position, 55 the head 52 of the corresponding link 51 lies in the lower portion of the opening 53. When a shutter is opened, that is raised, said head 52, through its engagement with the incline 57 on the shutter, is forced laterally 60 toward the right, as shown in Fig. 7, against the wall of the corresponding opening 55 in the actuating slide, forcing said slide toward the right and causing the clutch shifter to move the sliding clutch member into engagement with the fixed clutch member on the

end of the feed roll, the parts then being in the position shown in Fig. 7.

The specific construction of the independent voting mechanism forms no portion of the present invention and may be substantially as shown and described in Patent Number 914,007, above referred to, or otherwise, as preferred.

The paper strip in its passage from the backing plate 45 to the feed roll 43 is moved past marking mechanism, said mechanism applying a mark to the strip which is varied in accordance with the party of the voter, preferably by the same means which adjusts the primary locking mechanism above described in accordance with said party. As herein shown, the mark consists of a line of perforations whose location transversely of the strip indicates the party in question.

Referring to Figs. 1 and 2, 59 denotes a die plate riveted to the backing plate 45 and provided with grooves 60. Co-operating with said grooves 60 is a series of perforating wheels 61 carried by plungers 62 which are guided in openings in a block 63 supported by a bracket 64 secured to the framework. Said block 63 is provided beneath the ends of said plungers 62 with a guideway 65 in which is slidably mounted a rod 66 carrying a roller 67 adapted, as said rod is moved longitudinally, to engage the plungers 62 successively, thereby moving the corresponding wheels 61 upwardly and into operative relationship with the die plate 59.

68 denotes a link pivoted at one end to the slide rod 66 and at the other to an arm 69 projecting from a rock shaft 70 journaled in the framework. 71 denotes a second arm on rock shaft 70 to which is pivoted a link 72. The lower end of said link 72 is provided 105 with a rack 73 and is guided in a bracket 74 riveted to the casing, said bracket having a pin 75 which holds said rack 73 in engagement with a pinion 76 on the shaft 35.

As will now be seen, the key carrier 28 with its symbols or letters which are displayed through the index opening 30 serves as means for indicating the adjustment both of the primary locking mechanism and of the marking mechanism.

The pinion 76 (see Fig. 4) is of a length greater than the thickness of the link 72 so as to remain permanently in engagement with the rack 73 in all positions of the shaft 35 when said shaft is moved longitudinally 120 to disengage the pinion 37 from the rack 38. It will be observed in this connection that the longitudinal movement of the shaft 35 is limited in one direction by the engagement of the pinion 37 with the outer face 125 of the front wall of the casing 12, and in the other direction by the engagement of the pinion 76 with the inner face of said wall.

77 denotes a collar pinned to the shaft 35 130

adjacent the pinion 76, said collar being of a radius substantially equal to the radius of the outer ends of the teeth on said pinion 76. Collar 77 is provided with a flattened portion 78 whose surface lies opposite the bottoms of the teeth on said pinion 76. Engagement of the collar 77 with the edge of the rack 73 prevents movement of the shaft 35 to disengage pinion 37 from rack 38 except when the flattened portion 78 is opposite said rack 73. This occurs when key carrier 28 is in a position to bring its upper symbol, herein the letter "A", opposite index opening 30. When the pinion 37 is disengaged from the rack 38, the engagement of pinion 76 and flattened portion 78 of collar 77 with rack 73 prevents turning of shaft 35 and movement of link 72.

79 denotes a reading rule supported in a convenient position adjacent the paper feed roll and provided with graduations 80 corresponding in number and arrangement to the marking devices or perforating wheels 61, said graduations being identified by symbols corresponding to the symbols on the party markers and key carrier, herein shown as letters "A," "B," "C," etc.

The operation of the machine is as follows: A voter approaching the machine having declared his party, the knob 36 is turned to bring the corresponding symbol on the key-bar 28 opposite the index opening 30. The result of this is to operate the primary locking mechanism to unlock the voting members corresponding with the regular nominees of the party in question, locking all other voting members, and at the same time to adjust the marking mechanism so as to bring the roller 67 on the slide rod 66 opposite the plunger 62 carrying the perforating wheel which corresponds to that party. If now the voter elects to vote independently by opening an independent shutter 40, the actuation of the exit mechanism 45 when the voter leaves the machine will cause the paper strip to be fed past the perforating wheel corresponding to the voter's party and which has been rendered operative, thereby forming a line of perforations 50 lengthwise of the strip across the section used by the voter and positioned transversely of the strip in accordance with the voter's party. If the paper roll is not operated, that is to say if no independent shutter 55 or shutters are opened, but if the knob 36 is turned to adjust the mechanism for different parties, the slide rod 66 will be moved in its guide and the plungers 62 will rise and fall, causing the perforating wheels 60 to make a line of perforations across the paper. This line, however, comes midway between sections of the paper which are used by voters and cannot be confused with the regular identifying perforations which, 65 as above stated, extend in lines longitudi-

nally of the paper and across the sections used by the voters.

When the votes are counted after the closing of the polls, the paper strip is cut and unwound, being carried beneath the reading rule 79, the identifying graduations of which indicate the party affiliations of the voters who have used the independent paper roll at the primary.

When it is desired to remove the key carrier 28 for the purpose of arranging the keys thereon, the knob 36 is turned to bring the symbol "A" opposite the index opening 30, whereupon the shaft 35 is moved longitudinally by means of said knob to carry the pinion 37 out of engagement with the rack 38, when the key bar 28 may be withdrawn from the machine at the lower end of the cover plate 29. Until the return of the shaft 35 to its normal position the marking mechanism will be locked by the engagement of the pinion 76 and collar 77 with the rack 73, as above explained.

Having thus described my invention I claim:

1. In a voting machine, the combination with a casing having a voting aperture and means for feeding a paper strip past said aperture in a position to permit a vote to be written thereon, of means for making a longitudinal mark on said strip and means to control the position of said mark transversely of said strip.

2. In a voting machine, the combination with a casing having a voting aperture and means for feeding a paper strip past said aperture in a position to permit a vote to be written thereon, of a slotted die plate over which said strip is fed, a plurality of perforating wheels co-operating with said die plate for perforating said strip, and means for rendering said wheels alternatively operative.

3. In a voting machine, the combination with a casing having a voting aperture and means for feeding a paper strip past said aperture in a position to permit a vote to be written thereon, of a plurality of marking devices for marking said strip during the feed thereof and means independent of said feeding means for moving said devices alternatively into engagement with said strip.

4. In a voting machine, the combination with means for feeding a paper strip, of a plurality of plungers, markers carried by said plungers, and means for rendering said markers alternatively operative to mark said strip comprising a slide rod movable across the ends of said plungers and means carried by said slide rod for engaging said plungers successively to move said markers into engagement with said strip.

5. In a voting machine, the combination with means for feeding a paper strip, of a plurality of plungers, perforating wheels

carried by said plungers, and means for rendering said wheels alternatively operative comprising a slide rod movable across the ends of said plungers and means carried by said slide rod for engaging said plungers successively to move said perforating wheels into engagement with said strip.

5 6. In a voting machine, the combination with a casing having a voting aperture and means for feeding a paper strip past said aperture in a position to permit a vote to be written thereon, of a plurality of plungers, markers carried by said plungers, a slide rod movable across the ends of said plungers, and a roller carried by said slide rod for engaging said plungers successively to move said markers into engagement with said strip.

10 7. In a voting machine, the combination with means for feeding a paper strip, of means for marking said strip and means to vary the mark made on said strip comprising a slide rod, a rock shaft, an arm on said rock shaft connected with said slide rod, a second arm on said rock shaft, a link connected with said last named arm and provided with a rack, and a pinion for operating said rack.

15 8. In a voting machine, the combination with a casing having a voting aperture and means for feeding a paper strip past said aperture in a position to permit a vote to be written thereon, of means for marking said strip, and manually adjustable means to vary the mark so made and including a shaft, an indicator and means on said shaft for operating said indicator.

20 9. In a voting machine, the combination with means for feeding a paper strip, of means for marking said strip, means adjustable to vary the mark made on said strip and including a shaft, and means for indicating the adjustment of said varying means comprising a sliding bar provided with a rack and a pinion on said shaft coöperating with said rack.

25 10. In a voting machine, in combination, means for feeding a paper strip, means for marking said strip, means to vary the mark made on said strip including a slide rod, a rock shaft having an arm connected with said slide rod, a second arm on said rock shaft, a link connected with said last named arm and provided with a rack, a shaft provided with a pinion coöperating with said rack, an indicator provided with a rack, and a second pinion on said shaft coöperating with said last named rack.

30 11. In a voting machine, the combination with voting members and primary locking mechanism for said voting members comprising locking bolts and a key carrier provided with keys for operating said bolts, of means for feeding a paper strip, means for marking said strip, and means connected

with said key carrier for varying the mark made on said strip.

35 12. In a voting machine, the combination with voting members and primary locking mechanism for said voting members, of means for feeding a paper strip, means for marking said strip, means adjustable to vary the mark made on said strip, and means for simultaneously adjusting said primary locking means and said varying means.

40 13. In a voting machine, the combination with voting members and primary locking mechanism for said voting members comprising locking bolts and a removable key carrier provided with keys for operating said bolts, of means for feeding a paper strip, means for marking said strip and means detachably connected with said key carrier for varying the mark made on said strip.

45 14. In a voting machine, the combination with voting members and primary locking mechanism for said voting members comprising locking bolts and a key carrier provided with keys for operating said bolts, of means for feeding a paper strip, means for marking said strip, means adjustable to vary the mark made on said strip and including a shaft, and means on said shaft for operating said key carrier.

50 15. In a voting machine, the combination with voting members and primary locking mechanism for said voting members comprising locking bolts, a key carrier provided with a rack, and keys on said carrier for operating said bolts, of means for feeding a paper strip, means for marking said strip, means for varying the mark made on said strip including a shaft, and a pinion on said shaft coöperating with the rack on said key carrier.

55 16. In a voting machine, the combination with voting members and primary locking mechanism for said voting members comprising locking bolts, a removable key carrier provided with a rack, and keys on said carrier for operating said bolts, of means for feeding a paper strip, means for marking said strip, means for varying the mark made on said strip including a shaft, and a pinion on said shaft coöperating with the rack on said key carrier, said shaft being longitudinally movable to move said pinion into and out of engagement with said rack.

60 17. In a voting machine, the combination with voting members and primary locking mechanism for said voting members comprising locking bolts and a removable key carrier provided with keys for operating said bolts, of means for feeding a paper strip, means for marking said strip, and means permanently connected with said marking means and detachably connected with said key carrier for varying the mark made on said strip.

18. In a voting machine, the combination with voting members and primary locking mechanism for said voting members comprising locking bolts, a removable key carrier provided with a rack, and keys on said carrier for operating said bolts, of means for feeding a paper strip, means for marking said strip, means adjustable to vary the mark made on said strip including a link 5 provided with a rack, a shaft having a pinion coöperating with the rack on said key carrier, said shaft having a limited longitudinal movement to move said pinion out of engagement with said rack, and a second 10 pinion on said shaft coöperating with the rack on said link, said last named pinion being of a length to remain permanently engaged with said rack in all positions of said shaft.
19. In a voting machine, the combination with voting members and primary locking mechanism for said voting members comprising locking bolts and a removable key carrier provided with keys for operating 15 said bolts, of means for feeding a paper strip, means for marking said strip, means adjustable to vary the mark made on said strip, means detachably connected with said strip, means for preventing the disconnection of said operating means from 20 said key carrier except in a certain position of the parts.
20. In a voting machine, the combination with voting members and primary locking mechanism for said voting members comprising locking bolts, a removable key carrier provided with a rack and keys on said carrier for operating said bolts, of means 25 for feeding a paper strip, means for marking said strip, means for varying the mark made on said strip including a shaft permanently connected with said marking means, and a pinion on said shaft coöperating 30 with the rack on said key carrier, said shaft being longitudinally movable to move said pinion into and out of engagement with said rack.
21. In a voting machine, the combination with voting members and primary locking mechanism for said voting members comprising locking bolts and a removable key carrier provided with keys for operating 35 said bolts, of means for feeding a paper strip, means for marking said strip, means adjustable to vary the mark made on said strip, means detachably connected with said key carrier and permanently connected 40 with said varying means for operating said strip, means for preventing the disconnection of said operating means from said key carrier except in a certain position of the parts.
22. In a voting machine, the combination with voting members and primary locking 45 mechanism for said voting members comprising locking bolts and a removable key carrier provided with keys for operating said bolts, of means for feeding a paper strip, means for marking said strip, means to vary the mark made on said strip including a link provided with a rack, a shaft having a pinion coöperating with the rack on said key carrier, said shaft having a limited longitudinal movement to move said pinion out of engagement with said rack, a second pinion 50 on said shaft coöperating with the rack on said link, said last named pinion being of a length to remain permanently engaged with said rack in all positions of said shaft, and a flattened collar on said shaft adjacent said pinion.
23. In a voting machine, the combination with voting members and primary locking mechanism for said voting members comprising locking bolts, a removable key carrier provided with a rack, and keys on said carrier for operating said bolts, of means for feeding a paper strip, means for marking said strip, means adjustable to vary the mark made on said strip including a link provided with a rack, a shaft having a pinion coöperating with the rack on said key carrier, said shaft having a limited longitudinal movement to move said pinion out of engagement with said rack, a second pinion on said shaft coöperating with the rack on said link, said last named pinion being of a length to remain permanently engaged with said rack in all positions of said shaft, and a flattened collar on said shaft adjacent said pinion.
24. In a voting machine, the combination with a casing having a voting aperture and means for feeding a paper strip past said aperture in a position to permit a vote to be written thereon, of means for marking a longitudinal mark on said strip, means to control the position of the mark transversely of said strip, and a reading rule provided 10 with graduations by which the mark on said strip is read.
25. In a voting machine, the combination with a casing having a voting aperture and means for feeding a paper strip past said aperture in a position to permit a vote to be written thereon, of means for marking said strip during the feed thereof, and means for varying the mark so made.
